Paul Purchard,
Attorneys.

UNITED STATES PATENT OFFICE.

JAMES W. NORTH, OF PITTSBURGH, PENNSYLVANIA.

DAM.

Application filed January 27, 1925. Serial No. 5,062.

To all whom it may concern:

Be it known that I, JAMES W. NORTH, a citizen of the United States, residing at Pittsburgh, in the county of Allegheny and State of Pennsylvania, have invented 5 certain new and useful Improvements in Dams, of which the following is a specification.

This invention relates to dams and more in 10 particular to controllable dams used especially in connection with canal-locks and navigable rivers.

One of the principal objects of this invention is to provide a dam having a plurality of gates which may be operated simultaneously from a central point located on the bank of a river or canal. Another 15 object is to provide means whereby said gates may be operated with the least amount 20 of power to overcome the resistance of water.

A further object is to provide a dam which, when open, offers an unobstructed passage to the flow of water or to navigation. Additional features and advantages of this 25 invention will appear from the following description considered in connection with the accompanying drawing forming part of this application and in which:—

Fig. 1 is a perspective view showing diagrammatically the preferred embodiment 30 of my invention.

Fig. 2 is a top plan view of the construction shown in Fig. 1.

Fig. 3 is a side elevation of a dam-gate 35 unit in its erect position.

Fig. 4 is a front elevation of the erected dam-gate turned about ninety degrees.

Fig. 5 is a fractional top plan view showing the dam-gates in their open or collapsed 40 position.

Fig. 6 is a fragmentary view showing the preferred method of connecting a dam-gate with its supporting brace.

Fig. 7 is a view showing a constructive 45 detail of my invention.

Fig. 8 is a side elevation of the hinge of the supporting brace.

Referring to the drawing, it has been assumed that a canal-lock "A" is to be provided with a dam of my invention. As 50 shown, the dam is composed of a plurality of individual gates properly disposed to form a continuous dam when in their raised position. Each gate is composed of a horizontal turn-table 1 having a central pivot 2. 55 of suitable design to facilitate the easy ro-

tation of the turn-table and overcome whatever lifting action which may prevail, owing to the immersion of the gate in the water. Collapsibly mounted on the cross-member 3, fastened on the top of the turn-table, is a dam-gate 4 secured to said cross-member by means of hinges 5 which allow the folding of the gate in the up-stream direction only. When in erect position, the 60 dam-gate is assisted in resisting the pressure of the impounded water by a brace 6 which is connected to the top of the gate by means of a U-bolt 7 secured thereto and engaging a clevis 8 mounted at the upper 65 end of said brace. The lower end thereof rests upon a transverse tie 9, bolted to the bottom of the river lock, and is secured thereto by means of a hinge-connection 10 having a stop-lug 47 which permits the 70 collapsing of said brace in the same direction as the gate only.

Securely mounted on top of the turn-table, and preferably disposed at an angle of 45 degrees with the gate, is a radial arm 80 11 having a clevis 12 at its outer end by means of which it may be secured to an endless operating chain 13 which permits a 90 degree rotation of the turn-table on its axis, that is, until the erected gate occupies a 85 plane parallel with the flow of the water. When so rotated, it will be seen from Figs. 4 and 6 that the gate will bear against and be parallel with the brace 6.

Positioned at the top of the gate and substantially in vertical alignment with the pivot 2, is a swivel-ring 14 rotatably mounted on a metal plate 15 secured to the gate by means of the screws 16. To this swivel-ring is attached the gate lifting 90 chain 17.

The rotation of the turn-tables of the several units is performed simultaneously by means of the endless operating chain 13 which runs along the bottom of the river-lock and which is guided by means of the horizontal sheave 18, the two vertical sheaves 19 and 20, loosely mounted on a stationary shaft 21, and operated by the drive sheave 22 secured on the shaft of the motor or engine 23.

The lifting and lowering of the gates of the several units is also done simultaneously by means of a system of chains and sheaves. As illustrated diagrammatically 110 in Fig. 1, especially, the lifting chain 17 is connected to each of the swivel-rings 14 and

passed over a sheave 24 placed on top of the lock-bank and then carried downward around a second sheave 25, stretched across the bottom of the lock and guided by the 5 sheave 26 positioned on the opposite bank of the lock; thence it is wound around a drum 27 freely mounted on the shaft 28 of the motor, or engine, 29. This drum may be connected to the motor shaft by 10 means of any suitable coupling device, such as the claw-clutch 30 which is shown in Fig. 1 as being slidably operable by means of the lever 31 rockably mounted on a bracket 32 secured to the frame of the 15 motor. Drum 27 is called the gate-lifting-drum because its function is to raise the gates from their collapsed position.

The lowering or collapsing of said gates is effected by means of a chain 33 which is 20 connected to the swivel-ring of the end-gate at the right hand side, in Fig. 1. This chain is led downwardly and passed under and around a sheave 34 whence it is led upwardly over the gate-lowering-drum 35, 25 also freely mounted on the motor shaft 28 and engageable therewith by means of the clutch 30 and the lever 31.

In cases where the height of the folding gates 4 is greater than the radius of their 30 turn-tables, it becomes necessary to provide between the last gate unit and the wall of the river-lock a special side-gate to close up the additional space required by the projecting portion of the last gate when collapsed. In the installation shown in Figs. 35 1 and 2 it will be seen that the gates must be collapsed toward the right bank of the lock and that the side-gate will have to be located at the right side also. This gate is 40 composed of a gate-panel 36 hingedly mounted along the right hand wall of the river-lock by means of vertically aligned 45 hinges 37. The operation of this side-gate is preferably performed automatically by and simultaneously with the turn-tables by 50 using the mechanism shown in Fig. 2 and which consists of a gate opening chain 38 having one end attached to the side-gate at 39 and the other end attached to the edge 55 of the adjacent turn-table at 40. This chain is properly guided by the two horizontal 60 sheaves 41 and 42 suitably mounted on the bottom of the lock. The closing of the side-gate is effected in a similar manner by using 65 a second chain 43 having one end fastened on the opposite side of the side-gate, at 44, and the other end secured to the turn-table at 45. A sheave 46 is used to guide said chain. Suitable sealing-strips 48 are also 70 suggested in the drawing to reduce the leakage of water between the closed gates.

The operation of my dam is as follows: Assuming that the gates be in the erect, or closed, position required to impound the 75 water in the lock and that it be desired to

open the dam to let a ship go through said lock, the operator will start the motor 23 in the proper direction to cause the operating chain 13 to rotate the turn-tables a quarter of a turn in the counter-clockwise direction indicated in Fig. 2 by the curved arrows, that is, until the downstream sides of the gates bear against the braces 6 and the gates run parallel with the direction of flow of the water. The so rotated gates will be held in their erect position by the upward and backward tension exerted by the lifting chain 17 on them and the braces 6, which latter, as stated before can only be collapsed forward like the gates owing to 80 the stop-lugs 47.

After the water level in the lock has been lowered to that of the down-stream level of the river, the open gates are collapsed onto their respective turn-tables by slackening 85 the chain 17 and applying power to the lowering chain 33 by means of the operating lever 31, the clutch 30 and the drum 35, thereby offering an unobstructed passage 90 for the ship in the lock.

It will also be noted that the side-gate 36 will be rotated counter-clockwise by the similar rotation of the turn-tables, owing 95 to the chain and sheave mechanism used.

To close a lock, the operations to be performed are, of course, the reverse of the ones just described, that is, the gates are first raised by applying power to the lifting-chain 17 by means of the lifting-drum 27 which has been connected to the motor-shaft 28 by the clutch 30 through the instrumentality of the lever 31. The clockwise rotation of the turn-table into "closed" position is now performed by the chain 13, driven by the motor 23, which operation will also close the side-gate 36.

Obviously, the invention is not limited or restricted to the precise and exact details of the construction as illustrated and described, because it is susceptible of a variety of embodiments, and many minor mechanical changes may be made without in any way departing from the scope and field of this invention as set forth in the appended claims.

I claim:—

1. A dam comprising a turn-table and a gate collapsibly mounted thereon, and collapsible means for assisting said gate to withstand the hydrostatic pressure imposed 120 thereon and adapted to limit the rotation of said turn-table.

2. A dam comprising a plurality of units disposed in a row, each of said units consisting of a turn-table and a gate collapsibly mounted thereon, and means for simultaneously rotating said turn-tables.

3. A dam comprising a plurality of units disposed in a row, each of said units consisting of a turn-table and a gate collapsi- 130

bly mounted thereon, and unitary means for simultaneously rotating said turn-tables.

4. A dam comprising a plurality of units disposed in a row, each of said units consisting of a turn-table and a gate collapsibly mounted thereon, and means for simultaneously collapsing and erecting said gates.

5. A dam comprising a plurality of units disposed in a row, each of said units consisting of a turn-table and a gate collapsibly mounted thereon, and unitary means for simultaneously collapsing or erecting said gates.

10 6. A dam comprising a plurality of units disposed in a row, each of said units consisting of a turn-table and a gate collapsibly mounted thereon; unitary means for simultaneously collapsing or erecting said

gates, and means for assisting said gates to withstand the hydrostatic pressure imposed thereon, and adapted to limit the amount of rotation of said turn-tables.

7. A dam comprising a plurality of units disposed in a row, each of said units consisting of a turn-table and a gate collapsibly mounted thereon; a side-gate positioned at one end of said row and adapted to swing on a vertical axis; unitary means for simultaneously rotating said turn-tables; unitary means for simultaneously collapsing or erecting said gates, and means for operating said side-gate synchronously with and by said turn-tables.

25 30 35 In testimony whereof I affix my signature.

JAMES W. NORTH.
